UNITED STATES PATENT OFFICE

97,470

DESIGN FOR LACE

Bert Edson, Pawtucket, R. I.

Application October 5, 1935, Serial No. 58,838

Term of patent 3½ years

To all whom it may concern:

Be it known that I, Bert Edson, a citizen of the United States of America, residing in Pawtucket, county of Providence and State of Rhode Island, have invented a new, original, and ornamental Design for Lace, of which the following is a specification, reference being had to the accompanying drawing, forming part thereof, wherein, the figure is a plan view of a piece of lace showing my new design.

The characteristic feature of this design resides

in the provision of diamond shaped elements and wavy lines superimposed upon a solid background in one series of sections and thinner horizontal lines of openwork in a second series of sections, the sections of each series alternating with each other in the design.

I claim:

The ornamental design for lace, substantially as shown and described.

BERT EDSON.
